Attorney

UNITED STATES PATENT OFFICE.

ADELBERT WHITNEY, OF BIG TIMBER, MONTANA.

BOOK TROLLEY.

Application filed July 30, 1925. Serial No. 47,157.

This invention relates to book trolleys and more particularly to a device adapted to be attached to a desk for supporting large volumes such as track books and the like upon which work is being done.

An important object of the invention is to provide a device of this character by means of which the book may be readily moved from one position to another enabling work upon different parts of the book without the necessity of shifting the book or supporting the weight thereof.

A further object of the invention is to provide a device of this character which may be readily attached to a desk and which has means whereby the angle of the book to the horizontal may be adjusted.

A further object of the invention is to produce a device of this character which is simple in its construction and operation, durable and efficient in service and a general improvement in the art.

These and other objects I attain by the construction shown in the accompanying drawing, wherein for the purpose of illustration is shown a preferred embodiment of my invention and wherein:—

Figure 1 is a rear elevation of a book trolley constructed in accordance with my invention showing the same applied to a desk;

Figure 2 is a perspective of the trolley platform;

Figure 3 is an end elevation of the trolley and desk platforms;

Figure 4 is a perspective of the form of track employed.

Referring now more particularly to the drawing, the numeral 10 generally designates a framework adapted to be detachably connected to a table or desk. This framework includes a pair of parallel track sections 11 connected at intervals by braces 12. The end braces, indicated at 13, are extended to provide attaching arms 14 which may be connected with a desk by means of clamps 15 so that the framework 10 may be readily removed.

A roller supported platform 16 is provided comprising a pair of parallel bars 17 connected by suitable braces 18 and by axles

19 having at their ends grooved rollers 20, the grooves 21 of which are adapted to receive the tracks 11.

To one of the bars 17 is pivotally connected a desk platform 22, this bar having upstanding ears 23 coacting with the ears 24 carried by the desk platform to receive a hinge 25. The other of the bars is provided with slots 26 through which are directed threaded supports 27 pivoted to the desk plate 22 adjacent the opposite edge thereof. Each support 27 has associated therewith adjusting and clamping nuts 28 and 29 by means of which the extension of the support through the slots 26 may be regulated. By this means, the angular position of the desk plate 22 may be adjusted from a horizontal to an inclined position to suit the desires of the person employing the device. The lower edge of the desk plate has secured thereto a ledge 30 against which the lower edge of a book may rest to limit its movement. Stops 31 are preferably provided upon the tracks as a means for limiting the movement of the trolley thereon.

It will be obvious that the construction may be readily and cheaply produced and readily applied to or removed from a desk. It will also be obvious that this structure is capable of a considerable range of change and modification without materially departing from the spirit of the invention and I do not limit myself to such specific structure except as hereinafter claimed.

I claim:—

In a device of the character described, a framework including parallel tracks, a platform having rollers to engage the tracks and a desk plate having upon its under surface adjacent one edge thereof spaced ears, corresponding ears carried by one longitudinal edge of the platform and pivotally connected with the ears of the desk plate, means connecting the opposite edge of the desk plate and platform for vertically adjusting the last named edge of the desk plate.

In testimony whereof I hereunto affix my signature.

ADELBERT WHITNEY.
